UNITED STATES PATENT OFFICE.

AUGUSTUS BROCKELBANK, OF OSSINING, NEW YORK.

DESIGN FOR A SNAP-LINK.

SPECIFICATION forming part of Design No. 34,899, dated August 6, 1901.

Application filed May 29, 1901. Serial No. 62,440. Term of patent 14 years.

To all whom it may concern:

Be it known that I, AUGUSTUS BROCKELBANK, a subject of the King of Great Britain, and a resident of Ossining, in the county of 5 Westchester and State of New York, have invented and produced a new and original Design for a Snap-Link, of which the following is a specification, reference being had to the accompanying drawings, forming a part there- 10 of, in which—

Figure 1 is a plan view of a snap-link, illustrating the features of my design; and Fig. 2 is a side elevation of the same.

The leading feature of the design consists 15 in the design forming the subject-matter of the accompanying illustration. The snap-link includes the opposing loops A and A', which appear as formed from a single piece of material, and in the terminals B of the 20 loops, which extend in opposite directions over the connecting element of the loops, the design in its entirety resembling in general contour the figure 8. The terminals B of the loops continue from the loops in continuous 25 unbroken curves, which are reversed with

respect to each other in the opposite terminals, the extremity of one terminal dipping slightly toward the loop from which it is formed and the extremity of the other terminal dipping slightly toward its loop, while the 30 connecting portion at C, which joins the opposite loops, underlies the opposite terminals and dips below the said terminals, causing the link to present when viewed edgewise, as shown in Fig. 2, the appearance of flat end 35 portions and a depressed rounded central portion, as seen in the said figure.

Having thus described my invention, I claim as new and desire to secure by Letters Patent—

The design for a snap-link herein shown and described.

In testimony whereof I have signed my name to this specification in the presence of two subscribing witnesses.

AUGUSTUS BROCKELBANK.
